UNITED STATES PATENT OFFICE

WILLIAM E. VAN DORN, OF PASADENA, CALIFORNIA, ASSIGNOR TO UNION METAL PRODUCTS COMPANY, OF CHICAGO, ILLINOIS, A CORPORATION OF DELAWARE

METAL STRUCTURE FOR RAILWAY CARS

Application filed September 25, 1929. Serial No. 395,032.

My invention relates to the construction of railway cars and more particularly to metal end structures or walls for railway cars made of one or more metallic plates or panels formed with integral reinforcing, stiffening and bracing corrugations or embossments. However, this device may be incorporated in the construction of car side walls, floors, roofs, side doors or drop doors used in connection with railway cars of various types.

It is well known that the end walls of railway cars are more likely to be broken or otherwise injured than the side walls. This is due to the inertia thrusts and pressures caused by the shifting of the cargoes when the train starts or stops. These thrusts may be local, tending to distort the end in some particular spot, as, for example, when a piece of piping or lumber shifts lengthwise impacting a blow against the end wall of the car; or there may be a general tendency to break out the end wall as a whole or tear it away from the framing. For the purpose, therefore, of greater strength and durability, car ends have been constructed of metal plates corrugated or formed with ribs to impart the desired strength, rigidity and resiliency.

One of the principal objects of my invention is to provide a corrugated or embossed metallic end structure for railway cars in which the corrugations or embossments have a configuration and arrangement that impart to the structure a maximum capacity for resisting cargo thrusts, both local and general, static or quiescent, and with sufficient resiliency to prevent permanent distortion due to the thrusts of the loads, with a minimum weight of metal. It is important that structures of this sort should be as light as is possible, consistent with strength and durability, both for reasons of economy in manufacturing cost and also to keep the weight of the car at a minimum.

A further object is to provide a corrugated metallic wall element that is practically possible to manufacture. A further object is to provide a metallic wall element with corrugations or embossments that resist to a greater degree torsional stresses, as well as brace

the element, and the car end against diagonal side thrusts or weaving. Another object is to form a metallic plate with integral corrugations or ribs which impart to it a certain amount of strength and rigidity to resist loads imposed thereon and to so form the ends of the corrugations or ribs as to provide a certain amount of resiliency to enable the plate to deflect and return to its normal position without appreciable amount of permanent distortion.

My construction is an improvement over the arrangement of embossments shown in Patent No. 1,638,172 of August 9, 1927, because when the lengths of the center lines of the metal of the cross sections at the middles and adjacent the end portions of the embossments are equal to each other, the width and depth of the end portions is dependent upon the width and depth of the middles of the embossments and vice versa. In my arrangement, however, assuming the width and/or depth of the middles to be the same as the middles of the embossments of the Small Patent No. 1,681,811 then the width and/or depth of the end portions of my embossments can be made deeper and/or wider than is possible in the Small arrangement without increasing the lengths of the center lines of the cross sections of the metal. This means without increasing the stretch of the metal.

While the corrugations are shown pressed outwardly, and in horizontal arrangement, it is understood that the corrugations or embossments may be pressed inwardly or partially inwardly and partially outwardly from the original plane of the plate or the corrugations or embossments may be placed in any position; for instance, vertically or diagonally. The plates or panels may be positioned vertically or horizontally and applied to any type of railway car.

In the drawings:

Fig. 1 is an end elevation of a box car equipped with my invention.

Fig. 2 is a section on line 2—2 of Fig. 1.

Fig. 3 is an end elevation of a gondola car equipped with my invention.

Fig. 4 is a section on line 4—4 of Fig. 3.

Fig. 5 is a detail of a plate formed according to my invention.

Fig. 6 is a section on line 6—6 of Fig. 5.

Fig. 7 is a section on line 7—7 of Fig. 5.

Fig. 8 is a section on line 8—8 of Fig. 5.

Fig. 9 is a section on line 9—9 of Fig. 5.

The metallic plate is formed with a plurality of substantially parallel embossments or corrugations of substantially the same length which preferably terminate within the plate or adjacent the stiffener or frame member to which the plate is secured. These embossments are preferably substantially equal in width adjacent their middle and spaced apart distances substantially equal to their width and are preferably of equal depth so as to provide a configuration which is symmetrical in cross section about a line midway between the outermost portions of the embossments. (See Fig. 6.) In a steel plate such a configuration provides the maximum strength for the amount of material used. This cross section is preferably sinuous, as shown in Fig. 6, to provide resiliency as well as strength.

The alternate embossments 2 have their opposite ends divided to form a greater number of portions 3, which portions are preferably shallower than the middle 4 of the embossment and are substantially equal in width and spaced apart distances substantially equal to their width.

The embossments 5 between the aforesaid alternate embossments are not so divided and decrease in width from their middle toward their opposite ends to form narrower parts 6, which parts are preferably shallower and substantially equal in width to the above mentioned portions 3 of the divided embossments 2 and also preferably substantially equal in depth thereto. The distances between the said parts of the tapered embossments 5 and the adjacent portions 3 of the divided embossments 6 are substantially equal to the widths, respectively, of such parts and portions. This arrangement provides a configuration symmetrical in cross section about a line midway between the outermost surfaces of the parts and portions. This configuration is shown in Fig. 7. The parts 6 and portions 3 are preferably formed on curves to provide a sinuous configuration to give resiliency as well as strength.

The embossments are preferably of constant width and depth for a predetermined distance 7 on each side of the central line of the plate or car (or midway between the extremities of the embossments) to provide a simple means of adjustment of the lengths of the embossments to accommodate various requirements.

I prefer to proportion the divided (2) and undivided (5) embossments so that the length of the center line of the metal of a cross section of the embossments adjacent

their middle (as shown in Fig. 6) is substantially the same as the length of the center line of the metal of a cross section through the end portions 3 of the divided embossments 2 and the end parts 6 of the undivided embossments 5 (as shown in Fig. 7). This is a material manufacturing advantage, as it more evenly distributes the draw and stretch of the metal due to pressing the embossments in the plate.

In Figs. 1 and 2 I have shown my reinforced plate applied as the end wall of a railway box car, wherein the usual parts of the car are shown, such as draft sill 10; striking casting 11; end sill 12; end plate 13; roof 14; corner post 15; lining 16 and nailing strips 17.

In Figs. 3 and 4 the reinforced plate is used as an end wall of a gondola car wherein the reinforced plate is provided with a vertical flange 20 secured to the steel side wall 21 of the car and the upper edge of the plate is attached to the top chord 22.

In Figs. 5 to 9 inclusive the plate is shown in detail.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. A metallic plate formed with a plurality of substantially parallel embossments of substantially the same length, the alternate embossments having their opposite ends divided to form a greater number of portions and the embossments between said alternate embossments being not so divided.

2. A metallic plate formed with a plurality of substantially parallel equal width embossments of substantially the same length, the alternate embossments having their opposite ends divided to form a greater number of portions and the embossments between said alternate embossments being not so divided.

3. A metallic plate formed with a plurality of substantially parallel equal width embossments of substantially the same length, the alternate embossments having their opposite ends divided to form a greater number of equal width portions and the embossments between said alternate embossments being not so divided.

4. A metallic plate formed with a plurality of substantially parallel equal width embossments of substantially the same length, the alternate embossments having their opposite ends divided to form a greater number of equal width portions and the embossments between said alternate embossments decreasing in width toward their opposite

ends to form parts substantially equal in width to said portions.

5. A metallic plate formed with a plurality of substantially parallel equal width embossments of substantially the same length, the alternate embossments having their opposite ends divided to form a greater number of equal width portions and the embossments between said alternate embossments decreasing in width toward their opposite ends to form parts substantially equal in width to said portions with the distance between said parts and the adjacent portions being substantially equal to their width.

10 6. A metallic plate formed with a plurality of substantially parallel equal width embossments of substantially the same length spaced apart distances substantially equal to their width adjacent their middle, the alternate embossments having their opposite ends divided to form a greater number of equal width portions spaced apart distances substantially equal to their width and the embossments between said alternate embossments being not so divided.

15 7. A metallic plate formed with a plurality of substantially parallel equal width embossments of substantially the same length spaced apart distances substantially equal to their width adjacent their middle, the alternate embossments having their opposite ends divided to form a greater number of equal width portions spaced apart distances substantially equal to their width and the embossments between said alternate embossments decreasing in width toward their opposite ends to form parts substantially equal in width to said portions with the distance between said parts and the adjacent portions being substantially equal to their width.

20 8. A metallic plate formed with a plurality of substantially parallel equal width and equal depth embossments of substantially the same length, the alternate embossments having their opposite ends divided to form a greater number of equal width and equal depth portions and the embossments between said alternate embossments being not so divided.

25 9. A metallic plate formed with a plurality of substantially parallel equal width and equal depth embossments of substantially the same length, the alternate embossments having their opposite ends divided to form a greater number of equal width and equal depth shallower portions and the embossments between said alternate embossments decreasing in width and depth toward their opposite ends to form shallower parts substantially equal in width and depth to said portions.

30 10. A metallic plate formed with a plurality of substantially parallel equal width and equal depth embossments of substantially the same length, the alternate embossments

having their opposite ends divided to form a greater number of equal width and equal depth shallower portions and the embossments between said alternate embossments decreasing in width and depth toward their opposite ends to form shallower parts substantially equal in width and depth to said portions with the distance between said parts and the adjacent portions being substantially equal to their width.

35 11. A metallic plate formed with a plurality of substantially parallel equal width and equal depth embossments of substantially the same length, the alternate embossments having their opposite ends divided to form a greater number of equal width and equal depth shallower portions and the embossments between said alternate embossments decreasing in width and depth toward their opposite ends to form shallower parts substantially equal in width and depth to said portions with the distance between said parts and the adjacent portions being substantially equal to their width, the length of the center line of the metal of a cross section 40 of the embossments adjacent their middle being substantially the same length as the center line of the metal of a cross section through said portions and said parts thereof.

45 12. A metallic plate formed with a plurality of substantially parallel embossments of substantially the same length spaced apart distances substantially equal to their width adjacent their middle, the alternate embossments having their opposite ends divided to form a greater number of portions spaced apart distances substantially equal to their width and the embossments between said alternate embossments decreasing in width toward their opposite ends to form parts substantially equal in width to said portions with the distance between said parts and the adjacent portions being substantially equal to their width.
